CLAIM

The ornamental design for an inflatable mattress, as shown and described.

DESCRIPTION

FIG. 1 is a perspective view of an inflatable mattress showing my new design.

FIG. 2 is a front view thereof.

FIG. 3 is a rear view thereof.

FIG. 4 is a left side view thereof.

FIG. 5 is a right side view thereof.

FIG. 6 is an enlarged top view thereof.

FIG. 7 is an enlarged bottom view thereof.

FIG. 8 is a rear, left, bottom perspective view thereof.

FIG. 9 is an enlarged detail view of area 9 shown in FIG. 1; and,

FIG. 10 is an enlarged detail view of area 10 shown in FIG. 8.

The broken lines in the drawings depict portions of the inflatable mattress that form no part of the claimed design.

1 Claim, 10 Drawing Sheets
